CLAIM

The ornamental design for a stand for television receiver, as shown and described.

DESCRIPTION

1. Stand for television receiver

1.1 : Perspective

1.2 : Front

1.3 : Back

1.4 : Left

1.5 : Right

1.6 : Top

1.7 : Bottom

1.8 : Reference

The portions of the drawing disclosure shown in the color grey in Figures 1.1, 1.2, and 1.6 are for the purpose of illustrating portions of the stand for television receiver that form no part of the claimed design. The broken line showing

(Continued)

of a television receiver in Figure 1.8 is for the purpose of illustrating environmental structure and forms no part of the claimed design.

1 Claim, 5 Drawing Sheets
